DESIGN FOR AN ADVERTISING DISPLAY FIGURE OR ARTICLE OF SIMILAR NA- TURE

Charles A. Meyerowich, Staten Island, N. Y.

Application August 9, 1938, Serial No. 79,207

Term of patent 14 years

To all whom it may concern:

Be it known that I, Charles A. Meyerowich, a citizen of the United States and resident of Staten Island, county of Richmond, State of New York, have invented a new, original, and ornamental Design for an Advertising Display Figure or Article of Similar Nature, of which the following is a specification, reference being had to the accompanying drawing, forming a part thereof.

I claim:—

The ornamental design for an advertising display figure or article of similar nature, as shown.

CHARLES A. MEYEROWICH.
